(57) **CLAIM**

The ornamental design for a hair appliance as shown and described.

DESCRIPTION

FIG. 1 is a front perspective view of a hair appliance showing our new design;

FIG. 2 is a top perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of a portion indicated in FIG. 1; and,

FIG. 10 is a cross-sectional view taken along the section line 10-10 of FIG. 7.

The dash-dash lines in the figures show elements that form no part of the claimed design. The dash-dot lines in the figures show boundaries that form no part of the claimed design.

1 Claim, 6 Drawing Sheets
